UNITED STATES PATENT OFFICE.

CLARENCE W. CRANE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DROP-BOX-LIFTING MECHANISM.

Application filed January 18, 1927. Serial No. 161,923.

This invention relates to the box lifting mechanism of a drop box loom. In such looms, it is desirable that the boxes may be released and raised manually for certain purposes, or that they may be entirely removed from the loom, if desired, without changing the adjustment or setting of the box lifting mechanism. It is also desirable that the lifting mechanism be operatively connected 5 to the lifter rod, or to some element slidable thereon at a point adjacent the pivotal center of the lay.

It is one object of my invention to provide an improved construction in a drop box lifting mechanism, so designed that the lifting lever and the parts associated therewith will always remain in operative relation, even when the lifter rod is entirely removed therefrom. Further objects are to provide a 10 construction in which the lifting lever is permanently connected to a member slidable along the axis of the lifter rod, and to provide a construction in which said slidable member has a yielding or giveaway connection to the lifter rod.

My invention further relates to arrangements and combinations of parts which will be hereinafter described and more particularly pointed out in the appended claims.

A preferred form of the invention is shown in the drawings in which

Fig. 1 is a front elevation of parts of a drop box loom embodying my improvements;

Fig. 2 is an end elevation thereof, looking 35 in the direction of the arrow 2 in Fig. 1;

Fig. 3 is an enlarged sectional end elevation, taken along the line 3—3 in Fig. 1, and

Fig. 4 is a plan view of the parts shown in Fig. 3, looking in the direction of the 40 arrow 4 in said figure.

Referring to the drawings, I have shown a portion of a loom frame 10 supporting a rock shaft 11 on which is mounted the usual sword 12 for the lay 13 and also a bracket 45 14 for the drop box lifter mechanism. The drop boxes 15 are assembled in a drop box frame 16 secured to the upper end of a lifter rod 17. A drop box lifting lever 18 is selectively operated by pattern mechanism 50 (not shown) and is moved up and down to correspond to the desired position of the drop boxes 15.

My invention relates more particularly to improved connections between the lifting lever 18 and the lifter rod 17, which connections will now be described.

The bracket 14 on the rock shaft 11 has an upwardly and laterally extending projection 20 (Fig. 3), provided with an opening 21 adapted to receive and position a sleeve or bushing 22. The sleeve 22 is preferably flanged at the upper end, as indicated at 23, and may be secured in the projection 20 by a binding screw 24. The lifter rod 17 has a sliding bearing in the upper part 55 of the sleeve or bushing 22 and the lower part of the bushing is preferably recessed to provide clearance for the rod 17.

The axis of the sleeve 22 preferably intersects the axis of the rock shaft 11 and it 70 will be noted that the sleeve is held in fixed relation to the bracket 14 and rock shaft 11, and that it is oscillated therewith as the lay 13 moves back and forth.

A link 26 is pivoted at 27 to the lever 18 and the lower end of the link is pivoted on a stud 28 inserted through a slot 29^a in a connecting member 29 (Fig. 3). The link 26 is preferably adjustable lengthwise, as indicated in Fig. 1. The member 29 is freely 80 75 slidable on the outside of the sleeve 22 and has a suitable bearing thereon in every position of the lifting lever 18.

One member 30 of a giveaway connection is pivotally connected by a stud 31 to an offset arm 32 forming part of the sliding connecting member 29. A second member 33 of the giveaway connection is pivoted at 34 to the first member 30 and is yieldingly connected thereto at its upper end by a spring 90 85 35.

The giveaway members 30 and 33 are provided with notched projections 36 adapted to engage a stud 37 (Fig. 2) on a stand 38 which is slidably mounted on the lifting rod 17 and which is normally connected thereto by a stud 39, as shown more in detail in the previous patent to Santon and Bassett, No. 1,587,086, issued June 1, 1926.

Having described the details of construction of my improved lifting mechanism, the use and advantages thereof will be readily apparent. It will be noted that the sliding member 29 has a substantial bearing on the 100

sleeve 22 and that there is no possibility of displacement of the member 29 therefrom in any position of the lever 18.

Furthermore, the movement of the member 29 is along the axis of the sleeve 22, which intersects the axis of the rock shaft 11. Also the member 29 moves approximately equal distances above and below the axis of the rock shaft, so that the oscillating movement at the point of connection between the link 26 and the member 29 is reduced to a minimum.

The drop box lifter rod 17 may be released from the lifter mechanism by withdrawing the stud 39 and moving the rod up or down manually as desired. During such manual movement, all of the operative parts will remain operatively connected and no loose parts can be displaced. The drop boxes may thus be moved up or down at the will of the operator or may be entirely removed from the loom without disturbing the adjustments of the lifting mechanism.

Having thus described my invention and the advantages thereof, I do not wish to be limited to the details herein disclosed otherwise than as set forth in the claims, but what I claim is:—

1. In a drop box lifting mechanism, a rock shaft, a plurality of drop boxes, a lifter rod for said boxes, a lifting lever, a connecting member slidable along the axis of said lifter rod, an operating connection from said lever to said sliding member, and a link pivoted to said sliding member at its lower end and pivoted to said lifter rod at the upper end of said link, whereby said rod may be actuated from said lifter lever.

2. In a drop box lifting mechanism, a rock shaft, a plurality of drop boxes, a lifter rod for said boxes, a bearing sleeve for said lifter rod mounted to oscillate with said rock shaft, and having its axis substantially intersecting

the axis of said shaft, a lifting lever, a connecting member slidable on said bearing sleeve, and operating connections between said sliding member and said lifter rod. 45

3. The combination in a drop box lifting mechanism as set forth in claim 2, in which the bearing sleeve extends across the axis of the rock shaft, and in which the sliding member crosses the axis of said rock shaft in its normal operative movement. 50

4. The combination in a drop box lifting mechanism as set forth in claim 2, in which the bearing sleeve extends across the axis of the rock shaft, and in which the sliding member moves substantially equal distances above and below said axis. 55

5. In a drop box lifting mechanism, a rock shaft, a plurality of drop boxes, a lifter rod for said boxes, a bearing sleeve for said lifter rod mounted to oscillate with said rock shaft and having its axis substantially intersecting the axis of said shaft, a lifting lever, a connecting member slidable on said bearing sleeve, positive operating connections between said lever and said sliding member, and yielding operating connections between said sliding member and said lifter rod. 60 65

6. In a drop box lifting mechanism, a rock shaft, a plurality of drop boxes, a lifter rod for said boxes, a bearing sleeve for said lifter rod mounted to oscillate with said rock shaft and having its axis substantially intersecting the axis of said shaft, a lifting lever, a connecting member slidable on said bearing sleeve, positive operating connections between said lever and said sliding member, a connecting device detachably secured to said lifter rod, and a giveway connection between said sliding member and said connecting device. 70 75 80

In testimony whereof I have hereunto affixed my signature.

CLARENCE W. CRANE.
